UNITED STATES PATENT OFFICE

JOHN U. JONES, OF DALLAS, TEXAS.

ENGINE.

Application filed November 20, 1923. Serial No. 658,830.

To all whom it may concern:

Be it known that I, JOHN U. JONES, a citizen of the United States of America, residing at Dallas, in the county of Dallas and

5 State of Texas, have invented certain new and useful Improvements in Engines, of which the following is a specification.

This invention relates to new and useful improvements in engines.

10 The object of the invention is to provide an engine or motor which may be operated by oil, air or steam or any combination of these mediums.

A further object is to provide an engine 15 for use in conjunction with the valve device forming the subject matter of my application Serial No. 658,331.

A particular object is to provide a combination engine which may be manufactured 20 in standard sizes and readily converted from one fuel to another without a change in structure.

A very important object is to obtain a 25 greater capacity and more power in the same size of cylinders, pistons and other parts, now manufactured for predetermined horse power, as well as obtaining greater economy and continuity of service.

Another object is to provide a combination 30 oil and steam engine in which the steam in the cylinder is superheated by exchange with the radiation from the piston and whereby the piston is cooled and an auxiliary piston cooling medium is thus eliminated.

A construction designed to carry out the invention will be hereinafter described together with other features of the invention.

The invention will be more readily understood from a reading of the following 40 specification and by reference to the accompanying drawings, in which an example of the invention is shown, and wherein:

Fig. 1 is a horizontal cross-sectional view 45 of an engine constructed in accordance with my invention.

Fig. 2 is a side elevation of the same,

Fig. 3 is an enlarged sectional view of the fuel valve,

50 Fig. 4 is an enlarged sectional view of the nozzle,

Fig. 5 is an elevation of the atomizing head,

Fig. 6 is a cross-sectional view on the line 55 6-6 of Fig. 1,

Fig. 7 is a cross-sectional view on the line 7-7 of Fig. 1,

Fig. 8 is an enlarged sectional view on the line 8-8 of Fig. 1,

Fig. 9 is a cross-sectional view on the line 9-9 of Fig. 1,

Fig. 10 is a fragmentary longitudinal cross-sectional view of a modified form of engine, and

Fig. 11 is a detail of the fluid inlets. 65

In the drawings the numeral 10 designates the cylinder of a double acting engine surrounded by a cooling jacket 11 which may be suitably supplied and maintained. A piston head 12 is slidable in the cylinder 70 and has sumps 13 in each end. The cylinder has annular flanges 14 at each end, to one of which is bolted a right-angular head 15, while a similar head 16 is bolted to the flange at the other end of the cylinder. The 75 head 15 has a heating chamber 15', while the head is surrounded by a heating jacket 16'. The jacket 11 is suitably connected with the circulating cooling means usually employed in engines of this type. Suitable so means for supplying steam or other heating fluid is connected with the chamber 15' and jacket 16'.

The head 15 has an elbow 17 cast therein and surrounded by the chamber 15'. The head 16 also has an elbow 18 cast therein, said elbow being provided with a central bore 19, axially of the cylinder 10 and extending through a sleeve 20 cast on the elbow. A piston rod 21 extends from the piston 12 through its bore 19 and is surrounded by packing rings 22 sealed in the bore. The head 16 has a cooling space 23 exposing the elbow. An extension 24 has a flange 25 by which it is secured to the head 16. 90

The elbow 18 has a fuel duct 26 provided with three branches 26' spaced around the bore 19. In the end of each branch duct is screwed an atomizing nozzle 27 directed into the cylinder. Fluid ducts 28 also extend 100 through the elbow and open on the face of the head 16 within the cylinder. The elbow 17 has a central fuel duct 29 and fluid ducts 30 on each side thereof. In the cylinder end of the duct 29 is screwed an atomizing head, 105 (Figs. 4 and 5) composed of a disk 31 and through radial nozzles 32.

The head 15 has a boss 33, while the head 16 has a similar boss 34 at one side. Each boss and head has an inwardly tapered radial 110

bore 35 for receiving a tapered valve casing 36 which fits tightly therein and is provided with an outwardly directed flange 37, by which it is fastened to the boss. The valve mechanism for each head is the same and a description of one will explain both. This mechanism is substantially the same as that described in my co-pending application hereinbefore referred to. It will be noted that 10 the lower end of the valve case is surrounded by the cooling jacket 16' of the head.

The valve case 36 has a central tube 38 extending therethrough and projecting outwardly a short distance. At the inner end 15 of the tube I provide a valve chamber 39 into which is screwed a seat ring 40 (Fig. 3); while at the other end of the chamber is formed a valve seat 41. The chamber thus has valve seats at each end, the bore of the 20 ring communicating with the duct 26 or 29, as the case may be. A valve stem 42 extends through the tube and has a valve head 43 thereon disposed in the chamber 39. The head is dressed on both ends so as to engage 25 the ring seat when moved inwardly and to engage the seat 41 when moved outwardly.

The valve stem extends through a stuffing box 44 at the outer end of the tube. A cap 45 is fastened on the end of the stem and is 30 slideable in a cross bar 46 carried by standards 47 mounted on the flange 37. A roller 48 is journaled in the cap and engages an eccentric 49, an element of a valve operating means forming no part of this invention. 35 A collar 50 is mounted on the stem just under the cap and coiled compression spring 51 surrounds the stem between the end of the tube and the collar. This spring normally holds the valve head 43 against the seat 41.

A fuel supply pipe 52 enters the tube 38, inwardly of the stuffing box 44, and a second fuel pipe 53 enters the opposite side of the tube (Fig. 10). Air or steam or both may 45 be supplied through the pipe 52, while fuel oil is supplied through the pipe 53. It is to be understood that the steam and air may be omitted and the fuel oil alone utilized. The valve stem 42 within the tube has special 50 threads 42' (Fig. 3) which cause the fluids passing along the tube to take a helical course and whereby the molecules are more thoroughly broken up and a more complete mixture of the constituent elements is obtained. The charge ejected through the nozzles will be fully atomized and highly combustible.

The tube within the valve case is surrounded by a vertical annular chamber 54. In the lower end of this chamber are valve 60 seats 55 and spaced below these seats are seat rings 56 having central openings communicating with the ducts 28 or 30, as the case may be. Valve heads 57 having upper and lower dressed faces are arranged be-

tween the rings and the seats and engage the same at the ends of their strokes. From each valve head a stem 58 extends the chamber 54 and a stuffing box 59 in the outer end of the case. On each stem 58 a coiled spring 70 60 is confined under a collar 61, whereby the valves are normally seated on the seat 55. Suitable means, such as eccentrics 62 are provided for operating the valve heads 57 and engage rollers 63 mounted on the outer 75 ends of the stems 61.

The cylinder has a circumferential ring of exhaust ports 64 at its central portion communicating with an annular exhaust chamber 65 surrounding cylinder. When the 80 head 12 is at either end of its stroke the ports are uncovered to exhaust the fluid behind the piston. At the outer end of each valve case 36 is mounted a pair of inwardly opening check valves 66 connected with supply pipes 67. These valves arranged to open under a predetermined pressure to supply fresh air at atmospheric pressure or air from a storage tank to fill the chamber in the case 36 and pass to the cylinder. 85

In operation fuel charge, such as oil is supplied through the pipe 53 and air or steam or both are supplied through the pipe 52. This mixed fuel passes down one of the tubes 38, being given a whirling motion by 90 the thread 42; whereby the molecules are broken up and atomization is promoted. Of course fuel is supplied to cylinder at one end at a time.

When the piston 12 uncovers the exhaust 100 ports 64, the valve heads 57 will be in an intermediate position, shown at the left of Fig. 1, whereby the fluid which has been stored in the chamber 35 will pass through the ducts 28 to the cylinder and blow out the 105 scavenging gases through the said ports.

As the piston covers the exhaust ports on its compression stroke the valves 57 remain open, whereby the air which has been admitted through the valves 66, is compressed 110 in the chamber 54. These valves 57 remain open until just prior to the opening of the fuel valve 43 and upon closing, trap the compressed air in both the chamber 54 and the sump 13 of the piston. 115

When the valve 43 is opened the fuel charge is admitted to the cylinder and ignition takes place. Any suitable means for timing the valves may be employed. The air which is stored and compressed in the chamber 54 is released at the end of the power stroke of the piston, the valves 57 opening when the exhaust ports 64 are uncovered. 120

When the engine is operated entirely by steam the valves 43 may be fastened against opening and steam admitted to the chamber 54 through the pipes 67 or otherwise supplied thereto. The valves 57 will then be 125 timed to open at the ends of the stroke, those 130

at one end of the cylinder alternating with those at the other end thereof. These will be closed at the proper interval. Other fuel adjustments are easily possible. The valve cases 36 being self contained units and readily fitted into the heads 15 and 16 may be altered if necessary without changing the cylinder, head or other part. By manipulating the parts as described, the engine may be converted from oil to steam or air or any other combination, thus offering an economical power plant adjustable to the conditions which might arise.

In Fig. 10, I have shown a modified form in which the cylinder has a second set of exhaust ports 64' connected with a chamber 65'. The right hand of the cylinder is used for oil, the ports 64 being uncovered on the power stroke resulting from the ignition of the oil charge; while the ports 64' will be uncovered at the end of the steam power stroke. The heat radiated from the piston caused by the ignition of the oil fuel will be dissipated by the steam which will be thus superheated and the heat exchange will cool the piston to such an extent that auxiliary cooling means for the same will not be necessary. In this combination a very small quantity of steam will be admitted with the oil to assist in atomizing the oil and lubricating the cylinder. The exhaust from the oil end can be used to preheat the water for the steam.

Various changes in the size and shape of the various parts, as well as modifications and alterations may be made within the scope of the appended claims.

What I claim is:

1. In a double acting engine, a cylinder having a central exhaust opening, a piston working in the cylinder, heads at each end of the cylinder, each head having a fluid pressure chamber and a valve device arranged to admit a fuel charge and having provision for admitting fluid from said chamber to the cylinder on the working stroke of the piston and permitting a portion of the fluid to pass back into the chamber on the compression stroke of the piston for storage under pressure therein, and releasing said stored fluid when the exhaust opening by the piston is uncovered to blow out the gases remaining in the cylinder.
2. In a double-acting engine, a cylinder having a central exhaust outlet, a piston working in the cylinder, and heads at each end of the cylinder, each head having a fuel supply passage, a fluid pressure chamber, and valve mechanism operating to admit fluid to the cylinder from said chamber at the end of the working stroke of the piston, to cut off communication between the chamber and the cylinder on a predetermined preliminary portion of the movement of the piston on its compression stroke during which a portion of the fluid previously admitted to the cylinder is permitted to pass back into the fluid pressure chamber and to be compressed therein, and to then admit fuel to the cylinder during a portion of the remainder of the movement of the piston on its compression stroke and then cut off the flow of fuel.
3. In a double-acting engine, a cylinder having a central exhaust outlet, a piston working in the cylinder, a head at each end of the cylinder, each head having a fuel inlet and a fluid pressure chamber, a valve in each head governing the fuel inlet to supply a fuel charge to the adjacent end of the cylinder on the compression stroke of the piston therein, and a second valve in each head controlling communication between the adjacent end of the cylinder and the fluid pressure chamber, said second valve adapted to open to admit fluid from the chamber to the cylinder at the end of the working stroke of the piston, to remain open during a portion of the compression stroke of the piston to permit a portion of the fluid previously admitted thereby into the cylinder to be forced back and placed under compression in the chamber, and then close to cut off communication between the chamber and the cylinder.
4. In a double-acting engine, a cylinder having a central exhaust outlet, a piston operating in said cylinder and having a sump in each end thereof, heads at the ends of the cylinder, each having a fluid supply passage and a fuel supply passage opening into the cylinder and a fluid storage chamber communicating with said fluid supply passage, a valve in each head controlling the fuel supply passage for admitting fuel to the associated end of the cylinder on the compression stroke of the piston therein, and a valve in each head controlling communication between the fluid supply passage and the fluid storage chamber and operating on the working stroke of the piston to permit fluid to pass from said chamber to the cylinder through the fluid supply passage and operating on the compression stroke of the piston to permit a portion of said fluid to flow back through said passage to said chamber, and to cut off communication between the passage and chamber prior to the opening of said fuel valve.
5. In a double-acting engine, a cylinder having a central exhaust outlet, a piston operating therein, heads at each end of the cylinder, each head having a fluid pressure reservoir and a valve controlling communication between the same and the cylinder, a fuel supply passage having outlets communicating with the cylinder, atomizers arranged in said outlets, and a valve in said fluid supply passage having a stem portion provided with a helical thread forming with

- the wall of the passage a spiral channel for the flow of fuel.
6. In a double-acting engine, a cylinder having a central exhaust outlet, a piston operating in the cylinder, heads at the opposite ends of the cylinder, each provided with a fuel supply passage having a plurality of outlets and a plurality of fluid pressure reservoirs, a valve in each head controlling the fuel supply outlet, and valves in each head controlling the fluid pressure reservoirs, the latter-named valves being operative to admit fluid pressure to the cylinder on the working stroke of the piston and to permit a portion of the fluid pressure to pass back to the fluid pressure chambers on the compression stroke of the piston and to close communication between the compression chamber and cylinder prior to the opening of the fuel supply valve.
7. In a double acting engine, the combination of a cylinder having exhaust ports, a piston working in the cylinder, a valve case at each end of the cylinder having a central tube, an atomizing element in each end of the cylinder connected with the tubes, a valve for cutting off the supply from each tube to its atomizing element, and a pressure supply chamber in each valve case having a valve controlling communication with the cylinder, said valve operating on the working stroke of the piston to admit fluid from said chamber into the cylinder and on the compression stroke of the piston to allow a portion of the fluid to pass back into the pressure chamber for storage under pressure therein before closing communication between said pressure chamber and said cylinder.
8. In a double acting engine, having two sets of exhaust openings at its central portion, a piston working in the cylinder and alternately uncovering said sets of openings, valved means for admitting and associated means for atomizing a charge of fuel oil and compressing air at one end of the cylinder, and valved means for admitting steam to the opposite end of the cylinder at periods intermediate the ignition of successive compressed fuel charge.
9. In a double acting engine, a cylinder having two sets of exhaust openings at its central portion, a piston working in the cylinder and alternately uncovering said sets of exhaust openings, heads in the ends of the cylinder, valve devices mounted in the heads and communicating with the cylinder, one of said valve devices having a fluid inlet valve and a valve controlled storage chamber for delivering a charge of compressed fluid for scavenging the cylinder on the exhaust stroke of the piston, the valve of said storage chamber operating on the working stroke of the piston to permit fluid to pass from the pressure chamber to the cylinder and on the compression stroke of the piston to permit a portion of the fluid to pass back into the pressure chamber for storage under pressure therein before closing communication between said chamber and the cylinder, the other valve device in the other head having a fluid fuel admitting valve operating alternately with the fluid inlet valve of the first named valve device.
10. In a double acting engine, the combination with a cylinder having exhaust ports, of valve cases at each end of the cylinder, each case having a fuel charge conducting tube and a fluid pressure chamber, a fuel valve for controlling the passage of fluid through each tube in each case, and a second valve for each case controlling the passage of fluid between the cylinder and the chamber of said case, said second valve operating to permit fluid to pass from the pressure chamber to the cylinder on the working stroke of the piston and to permit a portion of such fluid to pass back into the pressure chamber on the compression stroke of the piston for storage therein, before closing communication between the storage chamber and cylinder.
11. In a double acting engine, the combination with a cylinder having exhaust ports, of valve cases at each end of the cylinder, each case having a fuel charge conducting tube and a fluid pressure chamber, a fuel valve for controlling the passage of fluid through each tube in each case, a second valve for each case controlling the passage of fluid between the cylinder and the chamber of said case, said valve operating on the working stroke of the piston to permit fluid to pass from the fluid pressure chamber to the cylinder and operating on the compression stroke of the piston to permit a portion of said fluid to pass back into the fluid pressure chamber for storage therein before closing communication between said chamber and the cylinder, and a check valved inlet valve connected with each valve case chamber for admitting a fluid thereto.
12. In a double acting engine, the combination with a cylinder having exhaust ports, a piston working in said cylinder, and means for admitting a fuel charge to each end of the cylinder, of a combination valve mechanism at each end of the cylinder having a valve-controlled storage chamber arranged to open upon the compression stroke of the piston to receive a compressed charge of fluid, said valve-controlled chamber being arranged to close to the cylinder prior to the admission of a fuel charge and to open to the cylinder after ignition to release the compressed fluid to scavenge the cylinder when the piston uncovers the exhaust ports of the cylinder.
13. In a double acting engine, a cylinder

having central exhaust ports and end heads, each end head including a boss extending at right angles to the cylinder axis and being provided with a fuel supply passage extending on a curved line between said boss and the adjacent end of the cylinder, a piston operating in said cylinder, and valve devices carried by the bosses for controlling the supply of fluid pressure through said passage to the cylinder for action on the piston at the ends of its opposite strokes.

14. In a double acting engine, a cylinder having centrally arranged exhaust ports and end heads, each head including a boss arranged at one side thereof and at right angles to the cylinder and an elbow extending between the boss and inner end of the head and provided with a fuel supply passage communicating with the cylinder, and valve devices carried by the bosses and con-

trolling the flow of fuel to the cylinder through said passages.

15. In a double acting engine, a cylinder having centrally arranged exhaust ports, hollow heads at each end of the cylinder, each head being formed with a cooling chamber, a boss extending from one side of the head and at right angles to the cylinder, and an elbow extending through the cooling space between the inner end of the cylinder and the boss, said elbow being provided with a fuel supply passage terminally communicating with the adjacent end of the cylinder and the boss, a valve chamber mounted in each boss and having a controlling valve therein governing said fuel supply passage, and means for operating the valves.

In testimony whereof I affix my signature.

JOHN U. JONES.
